UNITED STATES PATENT OFFICE.

JIM THOMAS, OF SHREVEPORT, LOUISIANA.

FURNITURE AND AUTO POLISH.

No Drawing.

Application filed May 26, 1925. Serial No. 33,044.

This invention relates to certain improvements in polishes and has relation more particularly to a polish of this kind especially adapted for use in connection with furniture and the like.

My improved polish comprises the following admixture;—linseed oil, 3 qts., pine rosin, 2 lbs., turpentine, 4 oz., beeswax, 2 oz.

These ingredients after being thoroughly mixed are cooked or boiled for approximately twenty minutes. After cooling, a composition is provided which may be employed to advantage in polishing furniture and the like.

The linseed oil is used to assure a smooth surface and also to harden the other ingredi-

ents employed. The turpentine serves as a dryer and eliminates the liability of a greasy effect when the polish is applied. The beeswax is employed to give a high gloss upon 20 the application of the polish while the pine rosin serves as a binder to hold the other ingredients together after they have been thoroughly mixed and boiled.

I claim:—

A polishing composition comprising a decoction of linseed oil, 3 qts., pine rosin, 2 lbs., turpentine, 4 oz., and beeswax, 2 oz.

In testimony whereof I hereunto affix my signature.

JIM THOMAS.
